UNITED STATES PATENT OFFICE.

ARTHUR MAZEPPA KING, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,824, dated April 30, 1872.

To all whom it may concern:

Specification describing a new and original Design for a Carpet, invented by ARTHUR MAZEPPA KING, Kidderminster, Worcester county, England.

The accompanying photographic illustration fully represents my new invention.

The design herein referred to consists of a new rectangular center figure for carpets, containing an inner square whose sides stand at an angle of forty-five degrees to those of the outer figure and of the lines which intersect the outer part of the latter, as shown. The inner square contains an ornamented star, and within the same a smaller square, as is also fully represented in the photograph.

I claim as my invention—

The design for carpets, as shown.

ARTHUR MAZEPPA KING.
